Martin V. Ingersoll
Inventor

By his Attorney,
John E. Earle

United States Patent Office.

MARTIN V. INGERSOLL, OF NORWALK BRIDGE, CONNECTICUT.

Letters Patent No. 106,166, dated August 9, 1870.

IMPROVEMENT IN BILLIARD-CUES.

The Schedule referred to in these Letters Patent and making part of the same

To all whom it may concern :

Be it known that I, MARTIN V. INGERSOLL, of Norwalk Bridge, in the county of Fairfield and State of Connecticut, have invented a new Improvement in Billiard-Cue; and I do hereby declare the following, when taken in connection with the accompanying drawings and the letters of reference marked thereon, to be a full, clear, and exact description of the same, and which said drawings constitute part of this specification, and represent in—

Figure 1, a side view, complete;

Figure 2, the first,

Figure 3, the second, and

Figure 4, the third operation of forming the head;

Figure 5, the ferrule; and in

Figure 6, a central section, enlarged.

This invention relates to an improvement in the manner of forming and attaching billiard-cue heads.

It is needless to specify the inconvenience and annoyance occasioned by the heads of common construction requiring frequent replacement, to overcome which is the object of my invention; and

It consists in forming the cue-head with a sleeve, to surround the cue, and with a holder below the head, and the said head secured to the cue by a band or ferrule around the said sleeve, and below the shoulder.

From leather or other suitable material, I cut a

cross-form, as seen in fig. 2, and this, when in a soft or moist state, I draw into the form seen in fig. 3. I then cut away the sides, and so as to form a shoulder, *a*, below the end, as seen in fig. 4, the reduced or sleeve portion being of a size to pass into a ferrule, *B*, as seen in fig. 5. I place the sleeve thus formed into a ferrule, *B*, and then, having reduced the end of the cue, insert it into the ferrule, as seen in fig. 6, pressing the sleeve between the ferrule and cue, (the sleeve and head being denoted in solid black,) taking care always that the head be slightly larger than the ferrule, as seen in fig. 6.

This construction affords an elastic head, and one which it is impossible to accidentally remove, and which must last until entirely worn out, thereby overcoming the many objections to the heads of common construction.

I claim as my invention—

A billiard-cue head formed with a sleeve to surround the cue, and constructed with a shoulder below the head, and secured to the cue by means of a band or ferrule, *B*, the end of which is covered by the shoulder below the head, substantially as described.

MARTIN V. INGERSOLL.
